FUZE MECHANISM

Ralph H. Severance, Fort Wayne, Ind., assignor to The Magnavox Company, Fort Wayne, Ind., a corporation
Filed Mar. 18, 1955, Ser. No. 495,279
9 Claims. (Cl. 102—71)

This invention relates generally to fuzes for projectiles or rockets, and more particularly to such fuzes wherein there are provided means for arming a fuze within a predetermined distance after the projectile or rocket has been launched, and wherein further means are provided for self-destruction of the projectile or rocket within a predetermined distance after the projectile or rocket has passed its target.

In accordance with conventional practice, projectiles or rocket fuzes include arming mechanisms having a timing clock adapted to arm a fuze within a predetermined time after the projectile or rocket has been launched. Clock mechanisms are relatively expensive and also relatively delicate, whereby it is extremely costly to manufacture delayed arming fuzes, and a fuze may not be armed after launching of the projectile or rocket because of a damaged timing mechanism.

In connection with rockets, it is especially important to provide a timing mechanism adapted to destroy the rocket within a certain time after it has missed an intended target. In case of aircraft launched rockets, it is particularly important to prevent explosion of spent rockets in friendly territory.

Accordingly, the principal object of this invention is to provide a fuze for projectiles or rockets having simple and inexpensive timing means for arming a projectile or rocket and for destroying the projectile or rocket in the event that the intended target is missed.

Another object of this invention is to provide a fuze arming and self-destroying mechanism which includes safety features adapted to prevent premature arming or self-destruction.

In accordance with this invention there is provided a fuze for projectiles or rockets comprising a means movable in response to the effects of acceleration for positioning a detonator in operative association with a firing mechanism, a timing mechanism normally effective to prevent movement of said means and responsive to the effects of acceleration for permitting movement of said means, firing means operatively associated with said detonator, and a timing mechanism normally locking said firing means and responsive to the effects of deceleration for unlocking said firing means.

The full nature of the invention will be understood from the accompanying drawings and the following description and claims:

FIG. 1 is a side elevation of a fuze embodying the invention.

FIG. 2 is a cross section taken on line 2—2 of FIG. 1.

FIG. 3 is a cross section taken on line 3—3 of FIG. 2.

FIG. 4 is a cross section taken on line 4—4 of FIG. 2 showing, in addition, the housing members in which the fuze of FIG. 1 is mounted.

Referring to the drawings, a fuze embodying this invention comprises a housing member 10 having a threaded portion 11 adapted to receive the warhead 12 of a rocket or projectile and having a second threaded portion 14 adapted to receive a casing member 15 which may be the propellant containing casing of a projectile or rocket. Within housing 10 there is provided a block member 16 within which is rotatably supported a substantially cylindrical detonator member 17 mounted for rotation on an axle 18. Axle 18 may be supported in removable insert 19. Within the detonator member 17 there is pro-

2

vided a detonating charge 20 which is normally retained in a non-detonating position, as indicated in FIG. 1.

The detonator member 17 is provided with a solid portion 22, the weight of which overbalances the diametrically opposite portion 23. Consequently, in response to acceleration of the projectile or rocket, the unbalanced member tends to rotate in a counterclockwise direction (FIG. 4). For preventing such rotation until after the projectile or rocket is launched, there is provided a timing and arming mechanism consisting of a slideably mounted cylinder 25 which normally engages flattened side 26 of detonator member 17. So long as cylinder 25 engages surface 26, the detonator cannot move out of its disarmed position. Cylinder 25 slides on a shaft 27 and is normally held in the illustrated position by means of an anti-creep spring 28, one end of which engages cylinder 25, and the other end of which engages a cover member 30 suitably fastened to the block 16. Cylinder 25 is filled with small beads 31, preferably formed of glass and having a diameter on the order of .0055 to .0065 inch. Shaft 27 has mounted thereon a node or plunger 21 having a diameter slightly smaller than the internal diameter of cylinder 25, and having sufficient clearance with respect to the cylinder wall to permit flow of beads past the outer edge thereof. Normal shocks to which a projectile or rocket may be subjected are insufficient to overcome the action of the anti-creep spring 28. Therefore, anti-creep spring 28 holds cylinder 25 in the position illustrated in FIG. 4, which is a forward position with respect to direction of flight of the projectile or rocket. Thus, forces resulting from acceleration tend to move the cylinder 25 and the beads contained therein to a rearward position where cylinder 25 is out of contact with the detonator member 17, leaving it free to rotate. In order to permit the detonator member 17 to rotate only in a counterclockwise direction (FIGS. 3, 4), there is provided a stop member 33 normally engaging a tongue 34 formed on a portion of the detonator member. This insures that this member will rotate only in a counterclockwise direction in response to acceleration forces. The rotor is also provided with a stop surface 35 whereby rotation of the rotor in response to acceleration positions the rotor with stop surface 35 in contact with stop 33, thereby to present the proper end 36 of detonator charge 20 into the path of a stab type of firing pin 37. The pin 37 is an integral part of a firing spring 38 mounted on a post 39, the ends of which are embedded in the walls of a spring receiving recess 40 in block 16.

For holding firing pin 37 and the spring 38 in cocked position, there is provided a trigger 42 pivotally mounted on a pin 43 embedded in the block member 16 as illustrated. Trigger 42 includes a firing pin receiving notch 44 for normally holding a firing pin 37 in a cocked position. Trigger 42 in turn is held in a cocked position by means of a second delay mechanism comprising a cylinder 45 slideably mounted within block 16 in a bore 46. Cylinder 45 is mounted to the rear of the block 16 as contrasted with cylinder 25 which is mounted in a forward position thereof, whereby cylinder 45 responds to decelerative forces. As in the case of cylinder 25, the cylinder 45 is mounted for sliding movement on a stationary shaft 41 positioned by means of a pair of discs 47 and 48 suitably fixed to block 16. Shaft 41 includes node or plunger 49, the outside diameter of which is slightly less than the inside diameter of cylinder 45. Beads 50 fill the rear end of cylinder 45, whereby decelerative forces tend to cause the beads and the cylinder to move in a forward direction in response to decelerative forces. Such forward motion normally is prevented by the depending portion 52 of detonator member 17 which

extends into the path of movement of cylinder 45. When the projectile or rocket is launched and becomes armed, this portion 52 of detonator member 17 moves out of the way of cylinder 45, whereby subsequent decelerative forces can cause movement of cylinder 45 out of the way of trigger 42, thereby to release firing pin 37.

In operation it may be assumed that detonator member 17 is in the position illustrated in FIGS. 3 and 4 where the detonating charge 20 is held in a safe position in which the fuze is disarmed. When the rocket or projectile is launched, the accelerative forces cause cylinder 25 and beads held therein to move rearwardly against the action of anti-creep spring 28; and since the beads flow past the node 31 at a rate determined by the rate of acceleration, there is a certain time interval between the time of launching and the time of operation of detonator member 17. The rate of flow of the beads is calculated with respect to probable rates of acceleration to arm the projectile or rocket when it will have travelled approximately three hundred feet along its trajectory. At this point cylinder 25 will free the detonator member 17, allowing it to rotate in a counterclockwise direction through an angle of ninety degrees, whereby the detonating charge 20 is in alignment with the path of movement of firing pin 37 and also in alignment with the explosive charge within the warhead.

It will be noted that the fuze embodying this invention is not illustrated in the drawing as including a firing mechanism adapted to respond to impact with a target. The firing mechanism forms no part of this invention, but it will be obvious to those skilled in the art that conventional firing mechanisms may be adapted to release a firing pin or to initiate detonation electrically.

If the projectile or rocket misses its target, and especially in the case of a rocket, deceleration will commence when the propellant charge has burned out. In response to such deceleration, cylinder 45 will move in a forward direction to release trigger 42 and firing pin 37, whereby the projectile or rocket destroys itself before falling into friendly territory. It is preferable that the cylinder 45 respond to such decelerative forces within a period of approximately one second.

From the foregoing description it will be apparent that this invention provides a simplified delay mechanism adapted to arm fuzes in projectiles or rockets. This mechanism is positive in its action and cannot respond to normal shock conditions created during shipment and storage, whereby there is adequate safety until the projectile or rocket has actually been launched along its trajectory.

The invention claimed is:

1. A fuze mechanism for projectiles and rockets comprising a block member adapted to be assembled in a projectile or rocket adjacent to the warhead thereof, a detonator movably mounted in said block member and normally positioned in inoperative relation to said warhead, whereby said projectile or rocket is disarmed and in a safe condition, means responsive to accelerative forces for moving said detonator into operative relation with said warhead, an arming delay device including a member normally positioned in said block in the way of movement of said detonator and movable in response to accelerative forces out of the way of said detonator to permit rotation of said detonator into said operative relationship with said warhead, a firing pin mounted in said block in alignment with said detonator when said detonator is in an operative position with respect to said warhead, a spring member connected to said block and said firing pin for moving said firing pin into firing engagement with said detonator, a trigger mounted in said block in the way of movement of said firing pin and normally holding said firing pin in a cocked position, and a self-destruction timing device including a member normally positioned in said block in the way of movement of said trigger and movable in response to longitudinal decelerative forces for releasing said trigger, said detonator including a stop member normally positioned in the way of movement of said self-destruction timing device for preventing movement thereof until said detonator has been moved into operative relation with said warhead.

5

2. A fuze mechanism for projectiles and rockets comprising a block member adapted to be assembled in a projectile or rocket adjacent to the warhead thereof, a detonator movably mounted in said block member and normally positioned in inoperative relation to said warhead, whereby said projectile or rocket is disarmed and in a safe condition, said detonator having means responsive to accelerative forces for moving said detonator into operative relation with said warhead, a firing pin mounted in said block in alignment with said detonator when said detonator is in an operative position with respect to said warhead, a spring member connected to said block and said firing pin for moving said firing pin into firing engagement with said detonator, a trigger mounted in said block in the way of movement of said firing pin and normally holding said firing pin in a cocked position, and a self-destruction timing device including a member normally positioned in said block in the way of movement of said trigger and movable in response to longitudinal decelerative forces for releasing said trigger, said detonator including a stop member normally positioned in the way of movement of said self-destruction timing device for preventing movement thereof until said detonator has been moved into operative relation with said warhead.

10 3. A fuze mechanism for projectiles and rockets comprising a block member adapted to be assembled in a projectile or rocket adjacent to the warhead thereof, a detonator rotatably mounted in said block member and normally positioned in inoperative relation to said warhead, whereby said projectile or rocket is disarmed and in a safe condition, said detonator having an off center weight responsive to accelerative forces for rotating said detonator into operative relation with said warhead, an arming delay device including a cylindrical member normally positioned in said block in the way of movement of said detonator and movable in response to accelerative forces out of the way of said detonator to permit rotation thereof into said operative relationship with said warhead, a plunger in said cylindrical member, and beads contained 15 in said cylindrical member and movable past said plunger for regulating the rate of movement of said cylindrical member in response to accelerative forces.

20 4. A fuze mechanism for projectiles and rockets comprising a block member adapted to be assembled in a projectile or rocket adjacent to the warhead thereof, a detonator movably mounted in said block member and normally positioned in inoperative relation to said warhead, whereby said projectile or rocket is disarmed and in a safe condition, said detonator having means responsive to accelerative forces for moving said detonator into operative relation with said warhead, an arming delay device including a container normally positioned in said block in the way of movement of said detonator and movable in response to accelerative forces out of the way of said detonator to permit rotation thereof into said operative relationship with said warhead, and means 25 within said container for controlling the rate of movement of said container in response to accelerative forces.

25 5. A fuze mechanism for projectiles and rockets comprising a block member having a detonator adapted to be assembled in a projectile or rocket adjacent to the warhead thereof, a firing pin mounted in said block member for movement into firing engagement with said detonator, a trigger mounted in said block in the way of movement of said firing pin and normally holding said firing pin in a cocked position, and a timing device including a cylindrical member normally positioned in said block in the way of movement of said trigger and movable in response to decelerative forces for releasing said trigger, a plunger in said cylindrical member, and a plurality 30

35 60 65 70 75

of beads in said cylindrical member for regulating the rate of movement of said cylindrical member.

6. A fuze mechanism for projectiles and rockets comprising a block member having a detonator adapted to be assembled in a projectile or rocket adjacent to the warhead thereof, a firing pin mounted in said block member for movement into firing engagement with said detonator, a trigger mounted in said block in the way of movement of said firing pin and normally holding said firing pin in a cocked position, and a timing device including a container normally positioned in said block in the way of movement of said trigger and movable in response to longitudinal decelerative forces for releasing said trigger, and means within said container for controlling the rate of movement of said container in response to longitudinal decelerative forces.

7. A fuze mechanism for projectiles and rockets comprising a block member adapted to be assembled in a projectile or rocket adjacent to the warhead thereof, a detonator movably mounted in said block member and normally positioned in inoperative relation to said warhead, whereby said projectile or rocket is disarmed and in a safe condition, said detonator including means responsive to longitudinal accelerative forces for rotating said detonator into operative relation with said warhead, an arming device mounted within said block member for longitudinal movement and positioned in the way of movement of said detonator for movement longitudinally of said block member by longitudinal accelerative forces out of the way of said detonator to permit movement of said detonator into operative relationship with said warhead, means in the way of movement of said device for impeding its movement and movable longitudinally out of the way of said device at a controlled rate by and proportional to longitudinal accelerative forces, a firing means mounted in said block in alignment with said detonator when said detonator is in an operative position with respect to said warhead, a release member normally positioned in said block in the way of movement of said firing means and mounted for movement longitudinally of said block member, and means in the way of movement of said release member for impeding its movement and movable longitudinally out of the way of said release member at a controlled rate by and proportional to longitudinal decelerative forces occurring before said projectile or rocket impacts a target for releasing said firing means for self-destruction of the projectile or rocket.

8. A fuze mechanism for projectiles and rockets comprising a block member adapted to be assembled in a projectile or rocket adjacent to the warhead thereof, a detonator movably mounted in said block member and normally positioned in inoperative relation to said warhead, whereby said projectile or rocket is disarmed and in a safe condition, said detonator including means responsive to longitudinal accelerative forces for rotating said detonator into operative relation with said warhead, an arming device mounted within said block member for longitudinal movement and positioned in the way of movement of said detonator for movement longitudinally of said block member by longitudinal accelerative forces out of the way of said detonator to permit movement of

5 said detonator into operative relationship with said warhead, a firing means mounted in said block in alignment with said detonator when said detonator is in an operative position with respect to said warhead, a release member normally positioned in said block in the way of movement of said firing means and mounted for movement longitudinally of said block member, and means in the way of movement of said release member for impeding its movement and movable longitudinally out of the way of said release member at a controlled rate by and proportional to longitudinal decelerative forces occurring before said projectile or rocket impacts a target for releasing said firing means for self-destruction of the projectile or rocket.

9. A fuze mechanism for projectiles and rockets comprising a block member adapted to be assembled in a projectile or rocket adjacent to the warhead thereof, a detonator movably mounted in said block member and normally positioned in inoperative relation to said warhead, whereby said projectile or rocket is disarmed and in a safe condition, said detonator including means responsive to longitudinal accelerative forces for rotating said detonator into operative relation with said warhead, an arming device including a member mounted within said block member for longitudinal movement and positioned in the way of movement of said detonator for movement longitudinally of said block member by longitudinal accelerative forces out of the way of said detonator to permit movement of said detonator into operative relationship with said warhead, a firing means mounted in said block in alignment with said detonator when said detonator is in an operative position with respect to said warhead, a release member normally positioned in said block in the way of movement of said firing means and mounted for movement longitudinally of said block member, and means in the way of movement of said release member for impeding its movement and movable longitudinally out of the way of said release member at a controlled rate by and proportional to longitudinal decelerative forces occurring before said projectile or rocket impacts a target for releasing said firing means for self-destruction of the projectile or rocket, said detonator including a stop member normally positioned in the path of movement of said release member for preventing movement of said release member and movable with said detonator out of the way of said release member when said detonator moves into operative relation with said warhead.
